UNITED STATES PATENT OFFICE.

GRACE G. DRAYTON, OF NEW YORK, N. Y.

DESIGN FOR A TOY BANK OR SIMILAR ARTICLE.

47,357.

Specification for Design.

Patented May 18, 1915.

Application filed March 1, 1915. Serial No. 11,382. Term of patent 3½ years.

To all whom it may concern:

Be it known that I, GRACE G. DRAYTON, a citizen of the United States, residing at New York, in the borough of Manhattan and State of New York, have invented a new, original, and ornamental Design for a Toy Bank or Similar Article, of which the following is a specification, reference being had to the accompanying drawings, forming part thereof.

view of a toy bank, showing my new design; Fig. 2, a side perspective view thereof; and Fig. 3, a rear perspective view thereof.

I claim:

The ornamental design for a toy bank or similar article as shown.

GRACE G. DRAYTON.
